UNITED STATES PATENT OFFICE.

JAMES L. POALK, OF MERCHANTVILLE, NEW JERSEY.

DESIGN FOR A LACE-FASTENER.

SPECIFICATION forming part of Design No. 33,157, dated September 4, 1900.

Application filed August 4, 1900. Serial No. 25,951. Term of patent 14 years.

To all whom it may concern:

Be it known that I, JAMES L. POALK, a citizen of the United States, residing at Merchantville, in the county of Camden and State of New Jersey, have invented and produced a new and original Design for a Lace-Fastener, of which the following is a specification, reference being had to the accompanying drawings, forming part hereof, in which—

Figure 1 is a top or plan view of a lace-fastener, showing the design of my said invention. Fig. 2 is a side elevational view of the fastener, and Fig. 3 is a longitudinal sectional view on the line 3 3 of Fig. 1. These three views are deemed essential to fully illustrate the shape and configuration of the lace-fastener of the design of my said invention.

As illustrated in the drawings, the leading or material feature of my invention consists of the particular shape or configuration of the fastener, comprising a circular perforated or eyelet head *a*, having formed integral therewith a tubular shank *a'*, the lower portion of which is flanged at *a*². From the upper portion of the perforated or eyelet head *a* the flat-surfaced and rounded-edge stem or arm *b* of the hook *b'* is bent upward at *b*² and the stem

or arm made tapering to the neck of the hook *b'*, which latter is curved slightly at the free end and concaved on the innerside *b*⁴, with the 30 surface *b*⁵ beveled about that portion of the hook, the device of my said invention presenting in appearance a circular eyelet-head, with a contracted or tapering stem or arm merging into a substantially goose-shaped neck- 35 hook, the inner surface of which neck is concaved and beveled where the hook portion joins the stem or arm of the device, and the said stem or arm, with its hook, being located slightly above the plane of the said eyelet-head, as clearly illustrated in Figs. 2 and 3 of the drawings.

Having thus described my invention, what I claim as new, and desire to secure by Letters Patent, is—

The design for a lace-fastener, substantially as herein described and illustrated.

In testimony whereof I have hereunto set my signature in the presence of two subscribing witnesses.

JAMES L. POALK.
